UNITED STATES PATENT OFFICE.

RALPH L. FORD, OF CHICAGO, ILLINOIS, ASSIGNOR TO INTERNATIONAL HARVESTER COMPANY, A CORPORATION OF NEW JERSEY.

VALVE AND TRIP-LOCK FOR PLANTERS.

1,382,771.

Specification of Letters Patent. Patented June 28, 1921.

Application filed November 29, 1920. Serial No. 426,926.

To all whom it may concern:

Be it known that I, RALPH L. FORD, a citizen of the United States, residing at Chicago, in the county of Cook and State of Illinois, have invented certain new and useful Improvements in Valves and Trip-Locks for Planters, of which the following is a full, clear, and exact specification.

This invention relates to valve mechanisms for check row corn planters and has to do more particularly with an improvement in locking means for the movable elements of the valve and the valve-actuating means in a valve mechanism of the type shown in the patent to Graham No. 757,399, April 12, 1904. The object of the invention is to provide a planter, having valve mechanism of the type referred to, with a simple and easily operable device by which the valve may be locked in open position for the purpose of drill planting and by which the plunger for actuating the valve as well as the check-fork and shaft carrying it are also simultaneously locked against movement relatively to the valve, thus allowing the spring pressed clutch tripping arm which is pivoted on the check shaft to be rocked on the shaft and held away from the clutch which controls the seed-feeding mechanism, without also causing the check shaft to rock and thereby lower the plunger into a position where it would obstruct the fall of the seed when drill planting, as will be clear to those skilled in the art to which this invention pertains.

The above objects are accomplished by providing the upper end of the plunger and the valve with a novel form of locking mechanism, comprising a spring pressed latch carried by the plunger and a complementary part, for locking engagement with the latch, carried by the valve in position to engage with the latch when the two are brought together, and by so arranging these elements as to cause no interference with the operation of the seed-dropping mechanism when the planter is being used for hill planting. With these objects in view my invention consists of a combination of elements and details of construction, or their equivalents, set forth in the following specification and defined in the claims. Referring to the drawings—

Figure 1 is a fore and aft vertical section

through the seed boot of the planter, the 55 full lines showing the valve closed and the dotted lines showing it locked in open position.

Fig. 2 is a rear view of the planter boot with wall removed and showing the valve 60 member in position therein.

Fig. 3 is a side view of the valve member alone.

Fig. 4 is a detail view of the back of the plunger, including the latch carried thereby, and

Fig. 5 is a plan view of the upper end of the plunger, on an enlarged scale, with the latch omitted.

The invention is shown in connection with 70 the usual planting unit of a corn planter, including the runner 10, boot 11, and hopper 12, the hopper bottom being provided with a seed dispensing mechanism including a 75 rotary seed plate driven in the usual manner by a transverse drive shaft 12'. There are usually two such units employed and their seed-feeding mechanisms are simultaneously controlled by a transverse rock shaft 13 which carries a check-fork 13^a at 80 either end for engagement with the check row wire to intermittently rock the shaft 13 and cause successive actuations of the seed-feeding and dropping mechanisms to plant the seed in spaced hills as common in this 85 class of devices. When it is desired to change from hill planting, or intermittent drop, to drill planting, or continuous drop, it becomes necessary to lock the valve mechanism in open position and to continuously 90 drive the seed-feeding mechanism, and my invention is directly concerned with improved means for locking and releasing the dropping valve and its actuating means.

The dropping mechanism in this instance 95 comprises two principal elements, namely, a tubular valve member 14 pivoted within the boot at 15 and having upper and lower valve plates 14^a and 14^b, the lower plate being pressed forwardly by a coiled spring 100 15^a placed between the rear wall of the boot and the valve plate and normally holding the valve member in position to close the seed-feeding outlet 16 and the drop outlet 17, and a plunger 18 pivotally suspended 105 within the boot on the rock arm 19 by pin 20.

The rock arm 19 is fixed to check shaft 13

and swings downwardly when the check shaft is rocked, forcing the lower end of the plunger against the lower valve plate 14^b and causing the valve member 14 to swing and open 5 the upper outlet 16 while discharging the seed accumulated in the lower part of the boot, as described in more detail in the patent above referred to.

As means for locking both these elements 10 against movement I provide the upper end of the plunger 18 with an eye 21 on its front face beneath which there is formed a grooved lug 22. The head of the plunger is rounded and formed with rearwardly extending parallel ears 23; the eye, grooved lug and spaced ears serve to receive a hook-shaped latch member 24 which has a longer arm positioned in the eye 21 and groove 22 which is pressed downwardly by a coiled 20 spring 25 which encircles it and bears between a pin or similar device 26 on said arm and the lower side of the eye 21. The shorter arm of the latch extends between and a little beyond the ears 23 and presents 25 a beveled end toward the valve member. Directly opposite the beveled end of the latch the valve member is provided with a complementary latching element which may consist of an eye 27 preferably formed integrally with the valve and having a rounded edge to coöperate with the beveled end of the latch. With the parts constructed 30 and arranged as above described, the operator has only to pull the lower end of plate 35 14^b rearwardly against the pressure of spring 15^a to cause latch 24 to engage eye 27 to lock the valve in the position shown by dotted lines on Fig. 1 and allow an unobstructed passage for the seed. To release the 40 valve and check-shaft the operator has only to push upwardly against the end of the long arm of latch 24, raising its other end from eye 27 against the pressure of spring 25, whereupon the valve member returns to 45 closed position under the pressure of spring 15^a. The important feature of my invention is that when the valve member is locked to the plunger, the plunger and therefore the check shaft is also locked against movement 50 and no accidental lowering of the plunger with consequent obstruction to the passage of seed can occur when the dropping mechanism is set for drill planting.

Having described my invention, what I claim as new is:

1. In corn planter valve mechanism comprising an independently movable member and plunger, the combination with said valve elements of locking means engageable with the valve member and plunger to lock them against relative movement. 55

2. In corn planter valve mechanism comprising an independently movable valve member and plunger, the combination with said member and plunger of means carried by one of said elements and engaging with the other to lock both against relative movement. 65

3. In corn planter valve mechanism comprising an independently movable valve member and plunger, the combination with said member and plunger of a lock comprising a latch carried by one of said elements and a complementary part on the other element engaging with said latch when the two 75 elements are brought together. 70

4. In corn planter valve mechanism comprising an independently movable valve member and plunger, the combination with said member and plunger of a lock comprising a spring pressed latch mounted on one end of the plunger and a latching eye on one end of the valve member engaging with said latch when the valve member is moved toward the plunger. 80

5. In corn planter valve mechanism including an oscillating arm and a plunger pivoted to said arm, the combination with the plunger of a latch adapted to engage an adjacent part of the mechanism to lock the 90 plunger and arm against movement. 85

6. In corn planter valve mechanism including an oscillating arm and a plunger pivoted to said arm, the combination with the plunger of means for locking the arm 95 and plunger in inoperative position.

7. In seed-dropping mechanism for planters, the combination of a rockable check shaft, seed-dropping mechanism, including a valve, means for intermittently opening said valve by rocking said shaft, and means for locking said valve in open position and simultaneously locking the check shaft against movement. 100

In testimony whereof I affix my signature. 105
RALPH L. FORD.
